REARWARDLY REMOVABLE REFRIGERATOR UNIT

John R. Replogle, Detroit, Mich., assignor, by
mesne assignments, to Copeland Refrigeration
Corporation, Mount Clemens, Mich., a corpora-
tion of Michigan

Application March 10, 1932, Serial No. 597,952

1 Claim. (Cl. 62—116)

This invention relates to the refrigeration art and has particular reference to the construction and arrangement of the parts, both of an insulated cabinet and of refrigerating mechanism 5 for employment therewith, which will be particularly adaptable for small commercial or household installations.

The principal objects of the invention are to provide a neatly appearing and compact refriger- 10 erator from which the refrigerating mechanism can be easily and quickly removed without its having been first disassembled or otherwise rendered inoperative and in which the refrigerating mechanism is so located as not to be apparent 15 from the exterior of the structure.

Another object of the invention is to provide a larger amount of refrigerating space in pro- 20 portion to the total dimensions of the structure than has been heretofore available in refrigerators, by so constructing and arranging the refrigerating mechanism within the exterior limits of a cabinet that the space occupied by the mechanism is not substantially greater than its over- 25 all dimensions.

Another object of the invention is to reduce 30 the weight of the refrigerating mechanism em- ployed in small refrigerators to the lowest pos- sible value in order to reduce the initial shipping cost on such units and also the shipping cost 35 on units returned to widely separated points of distribution, for service, inspection, salvage or resale.

Another object of the invention is to provide 40 a refrigerator in which the cabinet and refrigerating mechanism are totally independent in structure, thus rendering it possible to build each unit wherever labor, materials, technical knowl- 45 edge and other necessary requisites of construction can be obtained most economically and from whence the units can be shipped directly to a point of distribution in shipping crates, cars and other transportation equipment especially adapt- 50 able to the nature of each unit.

Another object of the invention is to simplify 55 the construction and reduce the cost of removable unit refrigerating systems, to permit their manufacture and sale in this and other countries to a larger number of purchasers than heretofore has been able financially to afford such uni- versally desirable product.

Another object of the invention is to so design 55 an insulated cabinet as to provide a small space in a rearwardly disposed and upper region there- of which can be made to house or accommodate a properly designed refrigerant condensing unit

and in front of which sufficient space will be provided in the interior of the cabinet for the accommodation of a suitably designed and ar- ranged evaporating unit, for cooling the interior of the cabinet and for freezing liquids internally 5 thereof.

Another object of the invention is to improve the performance of a refrigerating system by lo- cating the cooling unit thereof near the front of 10 a cabinet and adjacent the door opening therein where the highest temperature heretofore has prevailed in refrigerators, due to the greater rate 15 of heat absorption between the door and the cab- inet than prevails elsewhere therein.

The particular embodiment of the invention 15 disclosed herein for the purpose of illustration comprises generally a cabinet having a front opening therein closed by a door and constructed of internally and externally lined heat insulating slabs so arranged as to include inwardly pro- 20 jecting, vertically and horizontally disposed walls or partitions extending across the cabinet within an upper and rearwardly disposed region thereof thus forming a machine compartment within the 25 limits of a normally shaped cabinet exterior lin- ing. In this compartment are disposed the com- 30 pactly arranged elements of a refrigerant con- densing unit adapted to slide rearwardly of the cabinet through an opening formed in the lining for this purpose. Secured to the front of such 35 condensing unit and at one side thereof is a rear- 40 wardly removable section of the aforesaid verti- cally disposed insulating partition, and the front 45 of which provides a continuation of the cabinet interior lining. Between such section and the re- frigerator door is secured an evaporating unit for 50 the system which is removable with the aforesaid removable section through an opening in the par- tition in which the section normally is located.

In the drawings:

Figure 1 illustrates a fragmentary elevational view taken from the rear of a refrigerator embrac- 40 ing the principles of the invention;

Fig. 2 is a fragmentary horizontal cross-sec- 45 tional view taken through the refrigerator illus- trated by Fig. 1 immediately above the refriger- ating mechanism employed therein; and

Fig. 3 is a vertical sectional view of an upper 50 portion of the refrigerator illustrated by Figs. 1 and 2 as it might appear in the planes of lines 3—3 of Fig. 2.

Fig. 4 is a rear view of a refrigerator embrac- 55 ing the principles of the invention but employing a different form of condensing unit;

Fig. 5 is a horizontal sectional view of the re- 55

frigerator illustrated by Fig. 4 as it might appear looking in the direction of the arrows from line 5—5 thereof;

Fig. 6 is a vertical sectional view through a rear portion of the refrigerator illustrated by Fig. 4 as it might appear looking in the direction of the arrows from line 6—6 thereon.

Referring particularly to the drawings, a refrigerator 10, employed in practicing the invention, comprises a heat insulated cabinet 11 consisting of three vertically disposed walls 12, 13, and 14 merging in a bottom wall (not shown) and having an open side for receiving a vertically disposed front door 16. The rear wall 12, at its upper edge, terminates substantially below the side walls 13 and 14 and upon the upper extremity thereof, and in notches formed in the side walls 13 and 14 is secured the rear edge of a horizontally disposed partition 17. The forward edge 10
15 of this partition terminates at the lower extremity of a vertically disposed insulating wall 18 which in turn merges with the side walls 13 and 14 along the front edges of the aforesaid notches formed therein. The space within the cabinet 10
20 11 is closed at its upper extremity by an upper wall 19, extending between the upper limits of the side walls 13 and 14 and in front of the vertical partition 18.

The side walls 12, 13, and 14 are exteriorly covered by a metallic covering shell or casing 21 which continues upwardly beyond the horizontal partition 17 to provide the rear and side walls of a machine or condensing unit compartment 22 which is formed above the partition 17 and behind the partition 18. In the rear of this compartment the covering 21 is cut out, as is indicated at 23, to provide an opening through which the interior of the compartment is accessible from the rear of the cabinet. The partitions 17 and 18 are reinforced by a suitable frame 24 as likewise is the front of the cabinet, around the door opening therein, provided with a suitable frame 26.

The exterior lining 21 extends across the front of the cabinet and is there provided with inwardly turned flanges 27 which are secured by screws 28 around the inside of the frame 26 adjacent the outer edge thereof. The outer edges 29 of an inside lining 31, for the walls of the cabinet 11, likewise project into the door opening and are there secured, as by screws 32, to the inside of the frame 26 adjacent the inner edge thereof, and in spaced relation to the flanges 27. Secured by the screws 28 and 32, beyond the lining edges 27 and 29 and extending across the space therebetween, are insulating trim strips 33 which tend to give the refrigerator door opening a finished appearance and to prevent the conduction of heat from one edge thereof to another.

The insulated door 16 embraces a frame 34 having an outer covering 36 secured thereto which terminates adjacent the refrigerator door opening in an inwardly projecting flange 37. Secured to the inside of the door 16, by screws 38 projecting into the frame 34, is an inner door lining 39, the forwardly projecting edges 41 of which terminate a short distance inside of the flanged edges 37 of the exterior covering 36. The space between the interior lining 39 and covering 36 is occupied by a resilient gasket 42 secured to the door and which is compressed between the door and the front of the cabinet 11 to prevent the circulation of air between the exterior and interior of the cabinet.

75 The upper extremity of the cabinet 11 is cov-

ered by a removable top 43 having downwardly curved and beaded edges 44 around the four sides thereof which are held in proper relation to the cabinet by internally disposed supports 46. The top 43, which continues over and also covers the machine compartment 22, is provided with louvres 47 above the latter to permit the upward circulation of air therefrom, and a baffle strip 48 between the machine compartment and the space

8600<br

is connected by a coupling 83 to a liquid line 94. The suction line 88, the liquid line 94 and the power line 86 all project rearwardly through an opening formed in the wall section 52 which is

5 normally filled in a well known manner by a plastic insulating material indicated at 96.

In order to decrease circulation of air within the evaporating unit 68, the rear end of the sleeve 71 is closed by an end plate 95 having openings 10 therein through which the supports 67, secured inside the sleeve, extend.

Disposed directly across the machine compartment 22 and with the horizontal legs thereon resting upon the partition 17 directly behind the 15 opposite edges of the removable wall section 48 is a pair of angle members 98 disposed in opposite relation and with the laterally projecting portions of the vertical sections thereof abutting the surface of the partition 18 adjacent the opening 20 formed therein for the reception of the removable wall section. The parallel vertical portions of such brackets are secured to the outer surface of the frame 51 of the wall section by bolts 97 extending therethrough. Extending from adjacent 25 one end to another of the machine compartment 22 and secured by bolts 99 in spaced relation upon the horizontal portions of the brackets 98 are channel members 101 and 102 which are adapted to support the elements of a refrigerant condensing unit 103.

In order to secure the removable wall section 48 rigidly in place and to compress the gasket 57 between the flanges 56 and 59, the vertical and laterally extending portions of the brackets 35 98 are provided with openings adjacent the upper extremities thereof, adapted to receive studs 104 projecting outwardly through the lining 48 from bars 106 in which the studs are secured. The bars are secured by screws or other suitable fastening devices, not shown, to the portion of the frame 51 on opposite sides of the opening in the partition 18. Nuts 107 disposed on the outer ends of the studs 104 retain the upper portion of the wall section in position. In order to further secure the removable wall section, other relatively 40 long studs 105 are secured adjacent the lower extremities of the bars 106 to extend outwardly through openings formed in the lining 48 and beneath the horizontal portions of the angle members 98 where the outer ends thereof are secured by nuts 110 in openings formed in the downwardly and laterally turned ends of the horizontal portions of the angle members. The nuts 107 and 110 are removed when it is desired to remove 45 the refrigerating mechanism from the cabinet 11.

Disposed directly behind the removable wall section 48, and secured on studs 108 projecting through openings formed in the channel members 101 and 102, is a motor compressor unit 109 which comprises a part of the mechanism embraced in the refrigerant condensing unit 103. The motor compressor unit 109 embraces a cylindrical casing 111 having annular fins 112 extending over a considerable portion of the length thereof and in one end of which is formed a compressor cylinder 113. Legs 114, extending from the casing 111 and in which the upper ends of the studs 108 are secured, have coil springs 116 confined between the lower surfaces thereof, 50 and the upper surfaces of the channel members 101 and 102, and the horizontal portion of one of the angle members 98, on each of which one of the springs is supported. Nuts 117 secured on the lower ends of the studs 108, a considerable distance below the channel members

101 and 102 and the bracket 98 are tightened during transportation of the unit to prevent unnecessary motion of the motor compressor unit casing.

In the end of the casing 111 opposite the compressor 113 are removably secured the elements of an electric motor, not shown, which is employed in driving the compressor 113. The motor is connected in series with the thermostat 81 and the power line 86 by electrical conductors 10 115 extending between terminals 120 secured in the casing and a control box 125 secured upon the channel members 101 and 102.

The motor end of the casing 111 is closed by a head 118 which is secured thereto by screws 15 119 projecting outwardly from the flanged edge of the casing. A fitting 121 formed in the head 118 connects the suction line 88 with the suction side of the compressor 113, through the interior of the casing 111. The compressor section 20 of the casing is provided with a filling plug 135 through which oil may be charged if desired. The motor section of the casing has a similar plug 130 for discharging oil from the casing.

A head 122 secured to the opposite end of the 25 casing 111, by studs 123, provides means for obtaining access to the working parts of the compressor 113 located inside the casing 111 in this region.

The compressor 113 has a valve plate 124 and 30 a head 126 secured thereto by cap screws 127 and the compressed gas collected by the head 126 is discharged through a fitting 128, projecting from the head, into the upper one of a plurality of horizontally disposed and sinuously 35 wound sections 129 of a refrigerant condenser 131. The sections 129 are secured, one above another and adjacent the opposite ends thereof, between a pair of vertically disposed plates 132, the lower extremities of which terminate in flanges 133 which are secured by bolts 134 to the portion of the channel members 101 and 102 extending laterally to one side of the removable wall section 48 and behind the rigid part of the wall 18. Between the supporting plates 132 the condenser sections 129 are provided with vertically disposed fins 136 which are properly spaced on the sections of conduit to provide surface enough to cool the condenser 131 by natural draft circulation of air.

The sections 129 are each connected in series 40 at opposite ends to an adjacent section, thus permitting the liquid condensed therein to flow successively through the sections and to drain from the bottom section through an outlet connected to one end of a U-shaped refrigerant receiver 137. The sides of the receiver are disposed adjacent the lower ends of the plates 132 and upon the upper surfaces of the channel members 101 and 102 to permit circulation of air therethrough. The opposite end of the receiver is connected to the liquid line 94, through which liquid condensed by the condenser 131 is conducted through the expansion valve 82 and discharged at reduced pressure into the evaporating unit 68.

From the inside walls of the cabinet 11 project a plurality of supports 138 on which are disposed in spaced relation one above another a plurality of shelves, such as indicated at 139. One or more of the shelves 139 are disposed between the vertical partition 18 and the refrigerator door 36, at one side of the evaporator 68, while the remaining shelves beneath the partition 17 extend from the door 36 to the rear wall 70 12. On one of the shelves, which is suspended 75

between the side walls 13 and 14 in front of and at approximately the same level as the lower surface of the partition 17, is disposed a defrosting tray 141 in which water, thawing from the evaporator 68 during a defrosting operation, is collected.

In the structure illustrated by Figs. 4, 5, and 6, the cabinet and condensing unit structure is practically identical to that disclosed by the preceding figures except that a forced draft condenser is employed instead of a natural draft condenser. In such instance a small electric motor 160 is employed for driving a fan 161 which discharges a blast of air upon the motor compressor unit and induces a draft across the condenser 162 from a small portion 163 of the opening 23 formed in the exterior covering 21 at the rear of the machine compartment.

Such opening is formed by supporting a baffle 164 in front of the opening 23 from one end of the condensing unit to another. The lower edge of this baffle is secured to the outer ends of the horizontal portions of the frame members 98 by the nuts 110 while the upper edge of the baffle 164 is secured by screws 166 to the downwardly flanged edge 167 of a baffle 168 also extending from one end to another of the condensing unit but directly above the latter. The end of the baffle 168 opposite the condenser 162 is provided with an opening 169 through which the air drawn across the condenser and motor compressor unit by the fan 161 is discharged to the atmosphere through the louvres 47 in the cover 43. The edge of the baffle 168 opposite the flange 167 is provided with another downwardly turned flange 171, which is secured to the upper ends of the vertical sections of the angle member 98 by the nuts 107.

It will be apparent that whenever the condensing unit is removed from the machine compartment 22 the baffles 164 and 168 are simultaneously rendered removable from the condensing unit by the release of the nuts 104 and 110.

The condenser 162 comprises a vertically coiled conduit 173 which is flattened out to extend in parallel vertical planes substantially perpendicular to the channel members 101 and 102. The opposite extremities of such coil are secured in a parallel pair of supporting plates 174, the lower ends of which are secured by screws 176 to the outer edges of the channel members 101 and 102 adjacent the ends thereof remote from the motor compressor unit. Below the condenser 162 and also supported in openings formed in the end plates 174 is a refrigerant receiver 117 one end of which is connected to the lower end of the coiled conduit 173 while the opposite end thereof is connected to the liquid line 94. The opposite

extremity of the coiled conduit 173, like the conduit of the natural draft condenser 131, is connected to the outlet fitting 128 of the compressor 113.

The electric motor 160 is provided with a shaft 178 for driving the fan 161 and is supported by a bracket 179, the ends of which are secured inside the heads of a pair of the screws 123 to the head 122 of the motor compressor casing 111. Conductors 181 extending between the motor 160 and the control box 125 supply the electrical energy necessary for the operation of the fan.

It will be observed that there is practically no unemployed space in front or to the rear of the evaporator 68 and that practically no more space than required is provided for housing the compactly arranged elements of the refrigerant condensing unit 109.

In removing the refrigerating mechanism from the cabinet 11, it is only necessary to remove the nuts 107 which permits the condensing unit 103, the wall section 49, and the evaporating unit 68 to be removed through the opening 23 at the rear of the machine compartment 22, by a sliding movement of the angle members 98 along the upper surface of the partition 17.

While the structure as herein disclosed constitutes a preferred form and application of the invention, it is to be understood that other structures differing widely from that herein disclosed are within the scope of the invention as defined by the appended claim.

I claim:

In combination, a refrigerator cabinet having a fixed covering for the side and rear walls thereof, a chamber included between the upper rear portions of said side walls and having a fixed bottom and front wall, a top extending over said cabinet and said chamber, said front wall having an opening therein, a refrigerating unit removably supported on said bottom wall, said unit including a base, a pair of angle uprights extending upwardly from said base with one leg of each angle parallel to the side walls of the cabinet and the other leg thereof positioned at the rear of the first mentioned leg and parallel to the rear wall of said cabinet, said first mentioned legs being spaced from each other by a distance approximately equal to the width of said opening and projecting thereinto and said other legs overlapping said front wall along the margins of said opening and being secured thereto, an insulated plug carried between said first mentioned legs and closing said opening, and an evaporator mounted on the forward face of said plug.

JOHN R. REPLOGLE.
